UNITED STATES PATENT OFFICE.

LEON H. HAGOPIAN, OF PHILADELPHIA, PENNSYLVANIA.

DESIGN FOR A TARGET OR THE LIKE.

Application filed June 22, 1926. Serial No. 18,145. Term of patent 3½ years.

To all whom it may concern:

Be it known that I, LEON H. HAGOPIAN, a citizen of Armenia, residing at Philadelphia, in the county of Philadelphia and State of Pennsylvania, have invented a new, original, and ornamental Design for a Target or the like, of which the following is a specification, reference being had to the accompanying drawing, forming part thereof.

Fig. 1, is a face view of a target showing my new design;

Fig. 2, is an edge view thereof, the body of the target being in section to show the holes therethrough.

What I claim as novel is:

The ornamental design for a target or the like, as shown.

LEON H. HAGOPIAN.
